H. ROTH.
PROCESS OF MAKING SHOE SOLES.
APPLICATION FILED MAY 10, 1918.

Patented Nov. 25, 1919.

His Attorney.

UNITED STATES PATENT OFFICE.

HARRY ROTH, OF NEWPORT, KENTUCKY.

PROCESS OF MAKING SHOE-SOLES.

1,322,955.

Specification of Letters Patent. Patented Nov. 25, 1919.

Application filed May 10, 1918. Serial No. 233,698.

To all whom it may concern:

Be it known that I, HARRY ROTH, a citizen of the United States, residing at Newport, Campbell county, Kentucky, have invented 5 a new and useful Process of Making Shoe-Soles, of which the following is a specification.

This invention relates to a process of making shoe soles, wherein a sole is made of increased length without the use of additional 10 material.

In carrying out the process, a shoe sole blank is divided substantially throughout its heel seat portion by a split diagonal to 15 the surfaces of the blank, the separated sections moved relatively and longitudinally to the desired extent while maintaining the lapped relation, and such sections cemented together, to provide the required length of 20 sole.

By this method the original sole is made of increased length, without the use of any additional material whatever, and the newly 25 formed sole is solid, and for all manufacturing purposes equal to the original sole.

In the accompanying drawings I have illustrated the different stages through which a sole blank is passed in the course of its treatment and manufacture in order 30 to provide a finished sole somewhat longer than the original blank, and in said drawings—

Figure 1 is a plan view of a sole blank which is too short for making a sole of the 35 length desired.

Fig. 2 is a side elevation of the sole blank cut in a long inclined plane to provide two parts having matching surfaces, as shown.

Fig. 3 is a plan view of the sole blank 40 after the two parts have been secured together to form an elongated sole blank composed of the two connected parts.

Fig. 4 is a side elevation of the blank illustrated in Fig. 3.

Fig. 5 is a plan view of a finished sole made from the extended or elongated blank 45 illustrated in Figs. 3 and 4.

Fig. 6 is a view showing the upper side of the finished sole.

Fig. 7 is a side elevation of the finished sole illustrated in Fig. 6.

Fig. 8 is a cross sectional view on the line 8—8 of Fig. 6.

The sole blank illustrated in Fig. 1 is 50 composed of leather and is of a length which is too short for the use to which it is de-

sired to apply it. It is a well known fact that shoe manufacturers have encountered difficulty because of their inability, previous to this invention, to increase the lengths of 60 sole blanks in stock, and that occasions often arise creating a demand for larger quantities of sole blanks of increased length than the manufacturers have on hand. Various efforts have been made to overcome this difficulty but with unsatisfactory or indifferent 65 results.

My present invention provides a solution for this difficulty and has been employed with satisfactory results. As practised, my 70 invention consists in cutting a quantity of shoe blanks which are too short for use for the desired purpose in a long inclined cut extending forwardly and downwardly from a line very near the upper edge of the heel 75 portions of the blanks to a line about one-fourth of the length of the sole blank, more or less, so that two separated parts are provided from each sole blank, substantially as illustrated in Fig. 2. The part 1 is cut from 80 the part 2 in a long inclined plane, as shown, so that the rear portion of the part 1 is nearly of the same thickness as the part 2.

Next, glue or some other appropriate adhesive substance is placed upon one or both 85 of the matching inclined surfaces of the separated parts and said parts are placed together with the part 1 extending beyond the rear end of the part 2 the desired or necessary distance to make up the difference between the length of the original sole blank 90 and the length to which it is desired to extend the same. Pressure is then applied to the two overlapped parts by means of a press, or other similar means, which pressure causes the adhesive substance to bind and secure the two parts together. The extended sole blank thus constructed is illustrated in Figs. 3 and 4.

Next, the sole blank is cut or shaped to 100 the desired contour to form the sole, as shown in Figs. 5 and 6, in which it will be observed that the extended portion 1 constitutes an actual part of the sole at the heel portion thereof.

After being shaped, as shown in Fig. 5, the sole is cut or turned around the edge to provide a feather 3 for receiving a superimposed sewed part of the shoe. This feather is extended to the heel portion of 110 the sole which is nearly commensurate with the part 1 of the sole. Also, the inclined

channel 4 is made to form a space for the inseams of the shoe, the ends of the channel being slightly in front of the forward end of the part 1 of the sole.

5 From the foregoing it will be observed that by my invention a shoe sole is provided having a length in excess of the original blank from which the finished sole is made and that the thickness of the sole thus 10 constructed is nearly uniform throughout its length. This invention solves a practical difficulty and meets an existing need for means for making shoe soles of various lengths from blanks of different shorter 15 lengths in a very efficient manner.

The order in which the various operations are performed is unimportant since the elongation of the sole blank or sole may be

effected if the operations be performed in an order different from that described. I 20 do not restrict myself to these or other unessential details, but what I claim and desire to secure by Letters Patent is:—

The process of increasing the length of a shoe sole blank, consisting in dividing it 25 substantially throughout its heel seat portion by a transverse split diagonal to the upper and lower surfaces of the blank, and cementing together the split surfaces of the resulting sections with the heel end of 30 one section overlapping the heel end of the other section in order to obtain a blank of greater length than that of the original blank.

HARRY ROTH.
